UNITED STATES PATENT OFFICE

125,533

DESIGN FOR A SEAT BACK COVER

Robert E. Gates, Indianapolis, Ind., assignor to
Gates Manufacturing Company, Indianapolis,
Ind.

Application June 30, 1939, Serial No. 85,771

Term of patent 7 years

To all whom it may concern:

Be it known that Robert E. Gates, a citizen of the United States, residing at Indianapolis, in the county of Marion and State of Indiana, has invented a new, original, and ornamental Design for a Seat Back Cover, of which the following is a specification, reference being had to the accompanying drawings, forming a part thereof.

In the drawings, Fig. 1 is a view in front perspective of the cover;

Fig. 2, a front view thereof; and

Fig. 3 is a view thereof in rear perspective as viewed from the opposite side to that shown in Fig. 1.

The front face of the cover is made out of a material presenting a contrasting appearance to the top and rear sides of the cover.

I claim:

The ornamental design for a seat back cover, as shown and described.

ROBERT E. GATES.
